ATTORNEY

WITNESS: *J. W. Clark*

UNITED STATES PATENT OFFICE.

ABRAHAM J. GILDEEN, OF BROOKLYN, NEW YORK.

AUTOMATIC GAS CUT-OFF.

Application filed August 3, 1920. Serial No. 400,957.

To all whom it may concern:

Be it known that I, ABRAHAM J. GILDEEN, a citizen of the United States, residing at Brooklyn, in the county of Kings and State 5 of New York, have invented new and useful Improvements in Automatic Gas Cut-Offs, of which the following is a specification.

This invention relates to automatic gas 10 cut-offs and one of the principal objects is to produce a device of this nature which shall not be objectionably bulky or unsightly.

Another object is to produce a device of 15 this nature which shall be simple in construction, cheap to manufacture and efficient for the purpose for which it is designed.

Another object is to construct a device 20 of this nature of such parts and in such manner that it will not easily get out of order.

With these and incidental objects in view, the invention consists in certain novel construction and combination and arrangements of parts, the essential features of 25 which are fully set forth in the following description and claim and illustrated in the accompanying drawing comprising one 30 sheet, in which:—

Figure 1 is a side view partly in section of my improved device attached to a gas burner and showing the position assumed by the various parts when the gas is lighted.

Figure 2 is a similar view showing the position which the parts assume when the flame is extinguished.

This invention contemplates the provision of a safety gas extinguishing or cut-off means whereby the flow of gas will be automatically interrupted upon extinguishing the flame, and yet shall be compact and capable of being manufactured at a very reasonable rate.

Referring more particularly to the drawings, 1 represents an ordinary gas burner and 2 the tip thereof. The burner is drilled horizontally and through the apertures thus formed is passed a valve cylinder 3, provided with two vertically aligned apertures 4 and 5. The member 3 is provided at one

end with a closure 6 having a central aperture forming a bearing for a plunger rod 7. Rod 7 is provided with two collars or enlarged portions 8 and 9 between which is defined a space 10. Members 8 and 9 are a snug fit for the bore of member 3, and member 9 normally extends slightly from the open end of member 3 as shown in Figure 2, a coil spring 11 tending constantly to force the rod 7 in that direction by bearing against member 8. A limit of movement is set by a head 12 formed on rod 7. Normally the rod 7 is positioned with member 8 closing both apertures 4 and 5. 65

Secured to the top of the burner is a member 13 in which a depending rod 14 is adjustably secured by means of a set screw 15. The lower portion of rod 14 passes through an aperture in the upper portion of member 3 and has its ends arranged in sliding contact with member 9. Drilled in the side wall of the burner 1 is a small bleed hole 16 which is located opposite pin 14 and above which an aperture 17 is formed in 75 the member 13.

In operation, when the gas is to be lighted, the member 9 is pressed in level with the end of member 3, which brings aperture 10 into register with apertures 4 and 5 and permits a flow of gas to the tip 2 where it is lighted, the gas from bleed hole 16 being lighted at the same time. The small jet at 16 will cause the thermostatic pin to expand so that its lower end 80 will bind against member 9 and hold the same and rod 7 against the tension of spring 11. If the gas is blown out, pin 14 will contract and permit spring 11 to move the parts to the position shown in Figure 2 with the member 8 shutting off the flow of gas. If the large flame should be extinguished without extinguishing the small flame, then the small flame would serve as a "pilot" to re-light the large flame through aperture 17. 85

What is claimed as new is:—

A valve and burner structure including a valve casing having an aperture, a burner in communication with said aperture, a bleed opening in said burner, a valve plug 100 movable in the wall of said casing and a thermally actuated rod located at one side

of the burner and having one end freely extending into the valve casing and positioned with respect to the plug so as to positively and directly bind same against movement in the wall of said casing on expansion of said thermal means, a manually controlled portion on the plug and resilient

means for moving the plug to a closed position with respect to said aperture on contraction of said thermally actuated means. 10

In testimony whereof I have affixed my signature.

ABRAHAM J. GILDEN.
